UNITED STATES PATENT OFFICE.

MACK J. HEALY, OF BRADFORD, PENNSYLVANIA, ASSIGNOR, BY MESNE ASSIGNMENTS, TO CONSOLIDATED MACHINE COMPANY, OF BRADFORD, PENNSYLVANIA, A CORPORATION OF DELAWARE.

GLASS-DRAWING TOOL OR BAIT.

1,115,932.

Specification of Letters Patent.

Patented Nov. 3, 1914.

Application filed March 26, 1912. Serial No. 686,395.

To all whom it may concern:

Be it known that I, MACK J. HEALY, a citizen of the United States, residing at Bradford, in the county of McKean and State of Pennsylvania, have invented certain new and useful Improvements in Glass-Drawing Tools or Baits; and I do hereby declare the following to be a full, clear, and exact description of the invention, such as will enable others skilled in the art to which it appertains to make and use the same.

My invention relates to an improvement in glass drawing tools, or baits, the object being to provide means whereby the tool or bait may be readily detached from the cylinder without cutting or otherwise severing the glass, and it consists in the parts and combination of parts and in the details of construction as will be more fully described 20 and pointed out in the claims.

In the accompanying drawings, Figure 1 is a view in elevation of my improved drawing tool; Fig. 2 is a view in elevation taken at right angles to Fig. 1; Fig. 3 is a plan 25 view; Fig. 4 is a view similar to Fig. 2 showing the bait end of the tool opened to release the novel of the cylinder; and Fig. 5 is a view in vertical section of a modified form of tool.

30 The drawing tool comprises a head or bait, and a pipe 2, the latter being connected to the hub 4 and provided at its upper end with any suitable means (not shown) for its attachment to elevating and lowering devices and to the means for supplying the air to the cylinder through said pipe.

The head or bait is made in two sections 3 and 3^a, each of which is semi-circular in shape, and adapted when in their closed 40 position, as shown in Fig. 3 to form a complete circle. The section 3 of the head, is provided with the integral hub 4 so located as to be in the center of the head, when the two sections are in the closed position, and 45 this hub is recessed as shown in Figs. 2 and 3, to receive the projection 5 on section 3^a of the head, the said projection 5, forming in effect a continuation of the hub 4. The hub 4 is enlarged at 6, and the said enlargement 50 6, and the hub, constitute bearings for the pintle 7 on which the projection 5 of the section 3^a of the head is mounted.

From the foregoing it will be seen that the section 3^a of the head 1 normally rests in

contact with section 3 but may be turned on 55 pintle 7, away from said head so as to release the end of a novel of the cylinder confined within the head. In order to facilitate the manipulation of section 3^a, I prefer to provide the same with a handle 8 which may 60 be grasped to turn same on its pivot, and to lock the same in its closed position, I have shown the hub carrying the removable pin 9 which latter overhangs the upper end of projection 5 and prevents any turning move- 65 ment of section 3^a on pintle 7.

Each section of the head 1 is provided with a depending inwardly inclined semi-circular flange, which when the sections are closed, forms a continuous circular flange. 70 These flanges are provided interiorly adjacent the lower free ends, with an annular groove 10 forming a seat for the removable ring 11, which latter constitutes a continuous rigid shoulder which is engaged by the 75 glass, on to which the glass adheres when the head of the drawing tool is lowered into the molten glass, and which when the sections 3 and 3^a are separated may be removed from the drawing tool. The meeting faces of the 80 two sections of the head are machined so as to form a joint that will prevent undue leakage of air, or if desired a packing 12 such as asbestos, might be used for this purpose.

In the operation of the device the tool 85 or bait is lowered into the mass of molten glass until the ring 11 is submerged. The tool is then elevated and air admitted in the usual and well known manner to form a cylinder. After the cylinder has been drawn it 90 is lowered and the drawing tool detached from the hoisting and lowering means and the cylinder with the drawing tool attached, is laid horizontally on supports or horses. By now releasing and opening section 3^a of 95 the head or bait, the latter can be detached from the end of the cylinder and from ring 11, and is again ready for use. One advantage of this construction is that it frequently happens that after a cylinder is drawn, it 100 is desirable to cap and commence cutting from the end of the cylinder opposite the end attached to the drawing tool or bait. With the present form of drawing tool, the pipe must be held and properly supported until such time as the cylinder is capped off at the end to which the tool is secured. This cutting sometimes requires five minutes or

more, and during the time it is necessary that the tool be supported and manipulated by a man to prevent its weight from breaking the cylinder.

- 5 With my improvement, after the cylinder has been placed on its supports the tool may be at once disconnected by simply removing pin 9, opening up section 3^a and withdrawing section 3 from under the ring 10 11, thus leaving the ring attached to the end of the glass cylinder, which latter may then be capped and cut up at any convenient time thereafter. As the tool is used cold, or in other words is not heated before using, 15 it is absolutely self cleaning as the glass will not adhere to it, consequently does not interfere with the free opening of the section, and the separation of the ring 11 from the sections. With the old style tools, wherein 20 the head is an integral structure, the glass hardens within the recess inside of the air pipe, and it requires considerable time and work to remove this glass and properly clean the pipe which must be done before 25 it can be used again.

After the tool is removed from the end of the cylinder, the ring 11 remains attached to the glass, until the cap is detached and broken up which frees the ring and the 30 latter is then ready for use with the same or another drawing tool.

In Fig. 5, I have shown a sectional head for use without a ring. This construction is substantially that shown in the other figures, the ring being omitted. With this construction the glass enters the grooves and hardens sufficiently to sustain the cylinder. As the glass does not adhere to the metal head, the latter can be readily separated and 40 removed from the cylinder.

It is evident that numerous other means and devices may be resorted to for securing the two parts of the head together, for opening the movable section and for locking 45 the same in its closed position, hence I would have it understood that I do not confine myself to these details, but consider myself at liberty to make such changes as fairly fall within the spirit and scope of my invention.

50 Having fully described my invention what I claim as new and desire to secure by Letters-Patent, is:—

1. As a new article of manufacture, a glass drawing tool comprising an air pipe 55 adapted for detachable connection with lifting and lowering means, and a bait com-

posed of two semi-circular sections one of which is rigid with the air pipe and has an opening communicating with the passage through the air pipe, the other section of 60 the bait being hinged to the fixed section, each of said sections having a depending flange provided adjacent its lower edge with an internal shoulder.

2. As a new article of manufacture a glass 65 drawing tool comprising an air pipe adapted for detachable connection with lifting and lowering means and a bait composed of two semi-circular sections, one of said sections having a hub by which it is rigidly secured 70 to the air pipe and the other section hinged to the rigid section, each section of the bait having a depending flange provided adjacent its lower end with an internal shoulder, and means for locking the two sections of 75 the bait against opening movement.

3. A glass drawing tool or bait comprising a circular head made in two semi-circular sections, one of which is movable toward and from the other section, the said head 80 having a depending circular flange, and a removable ring seated on said flange.

4. A glass drawing tool or bait comprising a circular head made in two semi-circular sections one of which is movable with 85 relation to the other section, the said head having a depending flange, and a ring removably seated on and within the flange.

5. A glass drawing tool comprising a circular head composed of two semi-circular 90 sections each having a depending semicircular flange, the said flanges being grooved on their inner faces, and a continuous circular ring removably seated in said grooves.

6. A glass drawing tool comprising a circular head made in sections, and provided with a depending flange, and a removable ring seated within and on said flange. 95

7. A glass drawing tool comprising a two part circular head, one part having a 100 hub, and the other part hinged to the hub, a circular flange depending from said head, a ring removably supported within the flange and means for locking the two parts of the head together.

In testimony whereof, I have signed this specification in the presence of two subscribing witnesses.

MACK J. HEALY.
